BY his ATTORNEY

UNITED STATES PATENT OFFICE.

STANLEY YASKULKA, OF BOARDMAN, CONNECTICUT.

RAILROAD-TIE.

1,369,071.

Specification of Letters Patent. Patented Feb. 22, 1921.

Application filed September 29, 1920. Serial No. 413,567.

To all whom it may concern:

Be it known that I, STANLEY YASKULKA, a citizen of Poland, residing at Boardman, county of Litchfield, and State of Connecticut, have invented certain new and useful Improvements in Railroad-Ties, of which the following is a specification.

This invention relates to improvements in railroad ties, particularly of that class in which the rails are clamped to the ties by a stationary and a movable clamp member.

It is the principal object of the invention to provide a tie of this character which is of a simple and inexpensive yet durable construction.

A further object of the invention is the provision of a tie which allows of a quick and easy exchange of the rails as well as the movable clamp member.

Further objects and advantages of my invention will become known as the description proceeds, reference being had to the accompanying drawing, in which—

Figure 1 is a side view of a railroad tie constructed according to the present invention, partly in section.

Fig. 2 is a top plan view thereof with the parts assembled.

Fig. 3 is a view similar to Fig. 2 with the rail securing parts removed.

Fig. 4 shows in side and top plan view one of the clamping members, and

Fig. 5 is a detail view of a securing wedge.

The tie 10 of any preferred and suitable material is provided with the stationary clamping members 11 adapted to grip over the outer foot of the base flange 12 of a rail 13 while the inner foot part of the flange 12 is engaged by the gripping member 14 of a movable clamp element 15 having also a downwardly inclined outer member 16 extending into a chamber 17 of the tie and resting with its upper edge against a stop pin 18 within the chamber 17.

At its center the tie 10 has a wedge-shaped depression 19 in its center for the reception of a wedge 20 which is entered into said depression with its lower part 21, the upper part of which is provided with flanges 22 and 22' having perforations 23 and 24 for the passage of bolts 25 entering the tie 10.

The outer edges of the members 14 are beveled as at 26 to engage the outer faces of the wedge 20 when the parts are in place.

A bolt 27 is passed through the wedge and 55 the tie to hold the parts in adjusted position.

In operation, the outer rail foot flanges are placed under the stationary clamp 11 and then the movable clamp members 15 are placed within the central longitudinal 60 depression 28 of the tie 10 engaging with their upper members 14 the inner foot flanges of the rails and resting with the upper edges of their inclined lower members 16 against the bolts. When then the wedge 65 member 20 is placed in the depression 19 and secured to the tie by means of the bolts 25 passing through the perforations 23 and 24 of the flanges 21, 22 and the bolt 27 is secured in place, the parts will be clamped together in such a manner as to firmly hold 70 the rails in place upon the tie.

It will be obvious, that changes may be made in the general arrangement and construction of the minor details without departing from the spirit and scope of my invention.

What I claim as new and desire to secure by Letters Patent of the United States is—

1. In a railroad tie of the character described, the combination of the recessed and chambered tie with stationary clamp members adapted to engage the foot flanges on the outer sides of the rails, and movable clamp members adapted to engage the depressions of said tie, each of said last named members having an upper clamp member to engage the rail foot flange and a lower inclined member entering the tie chamber, a stop pin in the chamber adapted to be engaged by the lower inclined member, a wedge-shaped and flanged member, adapted to be placed into a central chamber of said tie and to engage with its outer wedge faces beveled inner ends of said movable clamp members, and means for securing the parts in their assembled position.

2. In a railroad tie of the character described comprising a recessed and chambered body, movable and stationary clamp members, the first named members adapted to engage the outer foot flanges of rails, said

movable clamp members having beveled inner and forked outer ends, the first ends engaging the upper face of rail foot flanges, the inner ends of said last named members adapted to engage the lower face of stop pins within the tie chambers, and a flanged wedge adapted to enter the central chamber

of said tie and to engage beveled edges of said movable members, and bolts to hold the parts in their assembled position.

10

In testimony whereof I have affixed my signature.

STANLEY YASKULKA.
